No. 747,130.

PATENTED DEC. 15, 1903.

G. C. BULTMAN.

WRENCH.

APPLICATION FILED MAY 15, 1903.

NO MODEL.

UNITED STATES PATENT OFFICE.

GEORGE C. BULTMAN, OF HARRISON, NEW JERSEY.

WRENCH.

SPECIFICATION forming part of Letters Patent No. 747,130, dated December 15, 1903.

Application filed May 15, 1903. Serial No. 157,309. (No model.)

To all whom it may concern:

Be it known that I, GEORGE C. BULTMAN, a citizen of the United States, residing at Harrison, in the county of Hudson and State of New Jersey, have invented certain new and useful Improvements in Wrenches; and I do hereby declare the following to be a full, clear, and exact description of the invention, such as will enable others skilled in the art to which it appertains to make and use the same.

This invention relates to improvements in wrenches.

The object of the present invention is to provide a wrench which is so constructed as to enable the sliding jaw thereof to be very quickly adjusted to adapt the wrench for use with various sizes of nuts, thereby overcoming the objectionable features common to the ordinary construction of wrenches in which the adjustment is effected through the medium of a screw.

A further object of the invention is to provide a quick-acting wrench embodying in its construction simple and efficient means to effect a locking engagement between the sliding jaw and the shank of the wrench, thus permitting the sliding jaw to be quickly slid along the shank to reduce the size of the space between the jaws of the wrench and at the same to enable the sliding jaw to be moved quickly from the stationary jaw to increase the size of the space therebetween, such adjustment being effected through the operation of suitable means adapted to release the sliding jaw from locking engagement with the shank.

A further object of the present invention is the provision of a wrench the parts of which are so assembled as to permit free and easy removal thereof, thus adapting the wrench to be readily repaired in the event of breakage of any of the parts and facilitating access to the elements involved in the construction of the wrench.

With these general objects in view and others which will appear as the nature of the improvements is better understood the invention consists, substantially, in the novel construction, combination, and arrangement of parts, as will be hereinafter fully described, illustrated in the accompanying drawings, and pointed out in the appended claims.

While the form of the invention herein shown and described is what is believed to be a preferable embodiment thereof, it will of course be understood that the same is susceptible of various changes in the form, proportion, and minor details of construction, and the right is therefore reserved to modify or vary the invention as falls within the spirit and scope thereof.

In the drawings, Figure 1 is a side elevation of a wrench constructed in accordance with the present invention. Fig. 2 is a similar view, the sliding jaw being shown in longitudinal section. Fig. 3 is a transverse sectional view on the line 3 3, Fig. 2.

Referring to the drawings, the numeral 1 designates the shank of the wrench, 2 the stationary jaw thereof, and 3 the usual handle, which may be of any suitable construction.

The shank 1 is provided at one of its edges with a series of ratchet-teeth 4, extending longitudinally thereof and approximately throughout the entire length of said shank, and said shank is also provided at the corners immediately contiguous to the teeth 4 with beveled faces 5 for a purpose to be presently stated.

Mounted upon the shank 1 and adapted to move thereon in the usual manner is a sliding jaw 6, which jaw is provided with a central passage or bore 7 to receive the shank 1, and said passage or bore 7 has at two of its opposite corners beveled faces or ways 8, designed to slide upon the faces 5 of the shank 1, and thus impart a free sliding movement to the sliding jaw 6 without liability of the latter engaging the teeth 4 of the shank and wearing the same by contact therewith.

The jaw 6 is provided at its interior and communicating with the passage or bore 7 with a central chamber 9, which chamber is also provided with a throat 10, whereby access may be had to the chamber 9 from the outer edge of the jaw 6. The chamber 9 is designed to receive a locking-pawl 11, which pawl is provided at its face immediately contiguous to the teeth 4 with ratchet-teeth 12, designed to engage the ratchet-teeth 4, and thus lock the pawl 11 in engagement with the shank 1. The pawl 11 is pivotally secured at its forward end in the chamber 9 through the

medium of a screw 13 or its equivalent, and thus said pawl may swing into and out of engagement with the teeth 4, as will presently more fully appear. The rear end of the pawl 11 is provided with a recess 14, one side of which is elongated to form a convex nose 15, and seated upon said nose is the forward end of a leaf-spring 16, the rear end of which is fixedly connected to the interior of the throat 10 through the medium of a screw 17, arranged within said throat. The point at which the screw 17 is positioned is immediately adjacent to the outer end of the throat 10, and thus it will be seen that said screw 15 may be readily removed by simply introducing a suitable instrument into said throat and engaging the head of the screw, and in the event that the spring 16 should become fractured the same may be readily replaced by 20 first removing the screw 17, whereupon a new spring is introduced into the throat 10 and seated upon the nose 15, after which the screw 17 is replaced.

In order to release the locking-pawl 11 from engagement with the ratchet-teeth of the shank, a trigger 18 is employed, and said trigger is pivotally held within the throat 10 by means of a screw 19, arranged in the sides of the jaw 6 and having its head at the exterior 25 thereof, as clearly shown in Fig. 1. The forward end of the trigger 18 is received by the recess 14, while the rear end of said trigger projects beyond the throat 10 and is thus positioned to be readily grasped by a finger of 30 the user of the wrench. By employing the screw 19 and arranging the same in the relation described said screw may be readily removed to effect removal of the trigger 18, and at the same time said screw provides a fulcrum upon which the trigger 18 swings.

In using the herein-described wrench if it be desired to reduce the size of the space between the stationary and movable jaws it is merely necessary to apply pressure upon the 45 movable jaw in a direction toward the stationary head 2. As the ratchet-teeth 4 incline toward the handle, the locking-pawl 11, under the stress of the spring 16, will readily slide over the teeth 4, and thus permit the 50 jaw 6 to be very speedily moved toward the stationary jaw 2. The spring 16, however, normally urges the pawl 11 into engagement with the ratchet-teeth 4, so that whatever may be the adjusted position of the sliding 55 jaw 6 the same is always held in such adjusted position by means of the locking-pawl 11, and thus when the wrench is applied to a nut the sliding jaw is effectually prevented receding therefrom. If now it be desired to 60 move the sliding jaw 6 away from the stationary jaw, it is merely necessary to place one finger upon the trigger 18, and upon pressure being exerted thereon said trigger will be swung upon its fulcrum, and by reason of the forward end thereof being received by the recess 14 the locking-pawl is swung upon its pivot 13 against the tension of the

spring 16, with a resultant disengagement of the teeth 12 from the teeth 4. As this disengagement removes all impediment to the 70 free-movement of the jaw 6 in a direction away from the jaw 2, said jaw 6 may be easily drawn toward the handle to the desired extent, whereupon as soon as pressure is released from the trigger 18 the spring 16 immediately acts upon the pawl and forces the teeth of the latter into engagement with the teeth 4, thus again locking the jaw 6 against any further movement away from the jaw 2. In the sliding movement of the jaw 6 it will 80 be noted that the faces or ways 8 of said jaw move upon the beveled faces 5 of the shank 1, and consequently the corners of the bore 7 do not engage the teeth 4, thus protecting the latter from wear and always maintaining 85 the same in a sharp condition to be engaged by the teeth of the pawl 11.

Having thus described the invention, what is claimed as new, and desired to be secured by Letters Patent, is—

1. In a wrench of the class described, the combination with the shank thereof provided with a series of ratchet-teeth and having beveled faces at the corners contiguous to said teeth, of a sliding jaw mounted upon said shank and provided with beveled faces or ways fitting upon the beveled faces of the shank to facilitate movement of the sliding jaw on the latter, a locking-pawl arranged in said sliding jaw and engaging the ratchet-teeth of the shank for locking the sliding jaw in adjusted position thereon, means for urging said pawl into engagement with said ratchet-teeth, and means for actuating said pawl to release the latter from engagement with said teeth.

2. In a wrench of the class described, the combination with the shank thereof provided with a series of ratchet-teeth and having beveled faces at the corners contiguous to said teeth, of a sliding jaw mounted upon said shank and provided with beveled faces or ways fitting upon the beveled faces of the shank to facilitate movement of the sliding jaw on the latter, a locking-pawl arranged in said sliding jaw and engaging the ratchet-teeth of the shank for locking the sliding jaw in adjusted position thereon, a spring for urging said pawl into engagement with said ratchet-teeth, and means for actuating said pawl to release the latter from engagement with said teeth.

3. In a wrench of the class described, the combination with the shank thereof provided with a series of ratchet-teeth and having beveled faces at the corners contiguous to said teeth, of a sliding jaw mounted upon said shank and provided with beveled faces or ways fitting upon the beveled faces of the shank to facilitate movement of the sliding jaw on the latter, a locking-pawl arranged in said sliding jaw and engaging the ratchet-teeth of the shank for locking the sliding jaw in adjusted position thereon, a spring for

urging said pawl into engagement with said ratchet-teeth, and a trigger for actuating said pawl to release the latter from engagement with said teeth.

- 5 4. In a wrench of the class described, the combination with the shank thereof provided with a series of ratchet-teeth and having beveled faces at the corners contiguous to said teeth, of a sliding jaw mounted upon said shank and provided with beveled faces or ways fitting upon the beveled faces of the shank to facilitate movement of the sliding jaw on the latter, a locking-pawl pivoted within said jaw and adapted to engage the teeth of the shank for locking said jaw in

adjusted position on said shank, said pawl being provided at its rear end with a recess one side of which is elongated to form a convex nose, a spring seated upon said nose for urging the pawl into engagement with the 20 teeth of the shank, and a trigger seated in the recess of the locking-pawl and adapted to actuate the latter for releasing the same from engagement with the shank of the wrench.

In testimony whereof I affix my signature 25 in the presence of two witnesses.

GEORGE C. BULTMAN.
